UNITED STATES PATENT OFFICE.

HAMILTON B. SPEER, OF BERKELEY SPRINGS, WEST VIRGINIA.

BARREL-TAPPING DEVICE.

1,286,821.

Specification of Letters Patent.

Patented Dec. 3, 1918.

Application filed June 4, 1918. Serial No. 238,158.

To all whom it may concern:

Be it known that I, HAMILTON B. SPEER, a citizen of the United States, residing at Berkeley Springs, in the county of Morgan, State of West Virginia, have invented a new and useful Barrel-Tapping Device; and I do hereby declare the following to be a full, clear, and exact description of the invention, such as will enable others skilled in the art to which it appertains to make and use the same.

This invention relates to an improved barrel tapping device, and an object of the invention is the provision of a device of this kind for tapping barrels either in vertical positions or upon their sides.

A further object is the provision of an improved barrel tapping device that can be used as a gage, whereby it is possible to ascertain the level of the liquid in the barrel.

A further object consists in an improved barrel tapping device for turning on and off the liquid.

In practical fields the details of construction may necessitate alterations falling within the scope of what is claimed.

The invention comprises further features and combination of parts as hereinafter set forth shown in the drawings and claimed.

30 In the drawings:—

Figure 1 is a view in perspective of a barrel showing the improved tapping device and gage applied.

Fig. 2 is an end view of the barrel showing the tapping device and gage in full lines in a vertical position, and in two dotted line positions, one for drawing the liquid from the barrel, and one whereby the amount of liquid in the barrel can be ascertained.

40 Fig. 3 is a vertical sectional view through the tapping device showing it applied to the end of the barrel which is in section.

Referring more especially to the drawings, 1 designates a conventional form of barrel, which in the present instance is disposed upon its side. A bunghole fitting 2 is fitted in a bung hole 3 of the end of the barrel, adjacent the chines. This bung fitting 2 has a flanged end 4. The bunghole fitting 2 extends through an opening of the coupling 5, whereby the flanged end may seat in the coupling. An elbow 6 is threaded into the coupling, thereby clamping the flanged end in place. A pipe section or tube 7 is threaded at 8 into the elbow. Carried by the upper end of the pipe section or tube 7 is a split

collar 9, the ears 10 of which receive a bolt 11, for drawing the collar tight but removably to the upper end of the pipe section or tube 7. This collar is provided with a 60 pair of spaced upwardly and laterally extending lugs 12, between which on a pin 13 the contracted shank 14 of the cap or cover plate 15 is pivoted. The shank has a handle 16. Projecting laterally and downwardly 65 from the collar is a lug 17, between which and the handle 16 a spring 18 is interposed acting to normally hold the cap or cover closed against the upper end of the pipe section or tube 7. An angle plate 19 is secured 70 in any suitable manner to the end of the barrel, substantially diametrically opposite the bunghole fitting. Pivoted upon a pin 20 carried by the angle plate is a member 21, provided with spaced forks 22 and a downwardly depending arm 23, the lug 24 of which is designed to contact with the end of the barrel to limit said forks in substantially lateral horizontal position. These forks when so disposed straddle the pipe section 80 or tube 7, thereby holding the same in a substantially vertical position. The flanged end of the bunghole fitting is not clamped tight enough to prevent swiveling of the coupling 5. In other words the pipe section may 85 be thrown or moved pivotally toward one side or the other, to assume such dotted line positions as indicated in Fig. 2. When the pipe section or tube 7 is moved to the dotted line position *a* in Fig. 2 and the cover or 90 cap 15 opened, the liquid in the barrel or other container may be drawn off into a receptacle, such as indicated. When the pipe section or tube 7 is moved to any position between the vertical position and the dotted 95 line position *a*, for instance such as indicated at *b*, and then the cap or cover 15 opened, the operator may ascertain the level of the liquid in the barrel or container. If desired the bunghole fitting may be connected to the side 100 of the barrel in close position to one end of the barrel. In this case the barrel is stood upon its end. However, the operation and the result attained by the operation of the barrel tapping device is the same. Any 105 form of checking device may be applied to the upper end of the tube or pipe section 7, and any form of holder or catch may be substituted for the forked member 21.

The invention having been set forth what 110 is claimed as new and useful is:—

The combination with a container, of an

outlet pipe communicatively swiveled to the lower part of one end of said container and disposed normally vertically in parallelism with said end, whereby said pipe may be 5 swung laterally in either direction at all times in parallelism with said end, a forked member pivotally mounted on said end and adapted to operate by gravitation, whereby the forks may straddle said pipe to retain it 10 vertically, means carried by and depending from the pivoted end of the member and

adapted to contact with said end of the container, whereby the member is limited in its gravity action to hold the forks straddling the pipe.

15

In testimony whereof I have signed my name to this specification in the presence of two subscribing witnesses.

HAMILTON B. SPEER.
